Inventor
Edward C. Mayhew.

By Attorney
Wason Fenwick Lawrence

UNITED STATES PATENT OFFICE.

EDWARD C. MAYHEW, OF NEW YORK, N. Y.

LAMP SHADE.

Application filed June 24, 1922. Serial No. 570,553.

To all whom it may concern:

Be it known that I, EDWARD C. MAYHEW, a citizen of the United States, residing at New York, in the county of New York and State of New York, have invented certain new and useful Improvements in Lamp Shades; and I do hereby declare the following to be a full, clear, and exact description of the invention, such as will enable others skilled in the art to which it appertains to make and use the same.

This invention relates to improvements in lamp shades, and the objects of the invention are to provide a bracket for such a shade which may be provided with means for supporting the shade upon an electric light globe; to prevent wabbling of the shade or displacement thereof; to enable the bracket to be stamped from a single sheet of metal; to provide fingers on the bracket for engagement with the globe, stamped from the metal forming a bracket; to secure simplicity of construction, ease of adjustment and neatness of appearance, and to obtain other advantages and results as may be brought out in the following description.

Referring to the accompanying drawing in which like numerals of reference indicate similar parts throughout the several views.

Figure 1 is a side elevation of a boudoir lamp showing my invention applied thereto;

Figure 2 is a top plan view of the bracket, and

Figure 3 is a side elevation of the bracket partially in section showing the same in its relation to an electric light globe.

In the specific embodiment of the invention illustrated in said drawing, the reference numeral 1 indicates in general a lamp to which the shade 2 is applied. It is to be understood that while I have shown a conventional type of boudoir lamp the invention may be applied to any kind of lamp wherein an electric light globe 3 has its point or tip 4 exposed.

The shade 2 comprises a bracket 5, preferably of metal, and a canopy or body portion 8 of any suitable material either transparent, semi-transparent or opaque. As I prefer to manufacture the lamp shade, the canopy 6 is of a semi-transparent paper on which any suitable design may be painted, printed or otherwise applied. I do not wish to be understood, however, as limiting myself to any particular material for this purpose. The bracket 5 is preferably stamped from a

single sheet of metal and provides a depending peripheral rim 7 to which the canopy or body portion 6 is riveted, stapled or otherwise attached. The rim is connected by suitable arms or spokes 8 to a central portion or hub 9 providing ample space for heat and light to pass upwardly from the globe 3. The central portion or hub 9 is preferably concave downwardly so as to substantially fit the end of said electric light globe 3. At the center of said hub is a suitable hole or opening 10 through which the point or tip 4 of the globe may project and thus prevent the bracket from displacement laterally from the globe. Depending from the central portion 9 are a plurality of resilient fingers 11 properly shaped and compressed toward each other to engage the side of the globe 3 and frictionally grip the same to hold the bracket firmly in place. It is to be understood that these fingers are so constructed and arranged as to co-operate with hole 10 in the center of hub 9 to prevent wabbling of the bracket as well as lateral displacement. Furthermore the resiliency of the fingers 11 is sufficient to enable the bracket to be attached to a globe, point 4 of which is projected downwardly, if so desired, and the fact that the present showing of the invention includes a lamp in which the point projects upwardly is not to be understood as restrictive of such use. As shown, the fingers are preferably integral with the metal forming the bracket, and are similar in shape to the spokes 8 except that their ends next the rim are severed therefrom so as to enable the said fingers to be bent downwardly. For purposes of attractiveness as well as greatest strength, the fingers 11 preferably alternate with the spokes 8, and are arranged so that each finger forms a continuation of a corresponding arm on the opposite side of the central portion or hub 9.

Obviously detail changes and modifications may be made in the manufacture and use of my improved lamp shade, and I do not wish to be understood as limiting myself except as set forth in the following claims when construed in the light of the prior art.

Having thus described my invention, I claim:

1. A bracket for an electric lamp shade comprising a central concaved apertured bulb engaging portion, a depending peripheral ring spaced therefrom and being

integrally connected thereto by means of radially extending spokes.

2. A bracket for an electric lamp shade comprising a central apertured bulb engaging portion adapted to receive the tip of a lamp bulb, radially extending spokes formed integrally with said central portion, a de-

pendent peripheral ring formed at the outer end of said spokes, and means supported by said central portion for engaging said lamp bulb for presenting lateral movement of the said bracket. 10

In testimony whereof I affix my signature.

EDWARD C. MAYHEW.
